D. B. CONKLIN

GAME

Filed Nov. 24, 1923

Inventor:
David B. Conklin,

By his attorney,
Harold D. Penney

UNITED STATES PATENT OFFICE.

DAVID B. CONKLIN, OF BROOKLYN, NEW YORK.

GAME.

Application filed November 24, 1923. Serial No. 676,764.

To all whom it may concern:

Be it known that I, DAVID B. CONKLIN, a citizen of the United States, and resident of Brooklyn, in the county of Kings and 5 State of New York, have invented certain new and useful Improvements in Games, of which the following is a specification.

The present invention has reference to a game apparatus or a game board, particularly designed for playing a game similar to the game of golf as played on a golf course, and in which a ball is caused to travel between various stations on the game board.

15 The object of the present invention is to provide a device of this character that will have the characteristics of the well known game of golf, and in which by the simple manipulation of the game board or device, 20 a ball is caused to travel or roll between various indentations indicating greens and cups and tees, that are formed by small shallow depressions in the plain surface of the enclosed game board; and which will 25 require considerable skill on the part of the operator to cause the ball to roll into the indicating depressions in a proper sequence, that are numbered or otherwise indicated on the device.

30 In the accompanying drawing illustrating one embodiment of my invention, Figure 1 is a plan view.

Fig. 2 is a section of the line 2—2 indicated in Fig. 1.

35 The device comprises essentially a game board or plate, indicated by 3 that may be composed of straw board, card board, or any material that will provide a plain surface, and which can readily receive slight depressions 4 of a spherical or concave form, so that the small playing ball 5 can be caused to roll into one of these slight depressions and remain there by bringing the board to a comparatively level position. 40 By slightly inclining the board 3 the ball 5 will roll out of such depression and pass along the board to another depression, direction of such movement depending on the manner in which the board is inclined by 45 the operator, who will hold the device in his hands.

The device is preferably in the form of a closed shallow box or receptacle having side walls 6, extending up from the four edges

of the bottom plate 3; and a glass top plate 55 7 is provided and preferably is permanently secured to the side walls, so that the ball 5 is movable in a closed chamber and cannot be touched by the operator in any manner.

As shown these indentations or depressions 4 are arranged in adjacent pairs, except the first one 10, that is shown surrounded by a rectangle 11, printed or marked on the base 3. The word Tee is printed adjacent this depression 10 to indicate the starting tee for the game. At a remote place from this tee a pair of depressions *c* and *g* are provided, and the depression *c* is surrounded by a circle 12, while the depression *g* is surrounded by a 60 small square outline 13 to indicate respectively, a cup and the green. This pair may have the number 1 on the board and indicate that the ball starts at the tee 11, is to be 65 rolled to 1 first to enter the cup *c* in the circle 12 and then pass to the green at 13. If desired lines 14 and 15 may be printed on the board to indicate the course of the playing ball.

From the green at 13, marked station 1, 70 the ball is to travel to a pair of depressions at a remote place, such as indicated by 2 on the board, that is a second station, where there is a cup *c* into which the ball is then 75 played, that preferably passes along the line 16. The ball is next played into the green depression at 2 which completes the second station. In like manner the ball is played 80 in succession to the similar stations *c* and *g* that are numbered 3, 4, and so in succession 85 up to the pair numbered 17, from which the ball is played to the final cup indicated by 18.

It will thus be seen that this corresponds 90 to an 18 hole course, and the ball is played 95 from station to station in the paths indicated until it finally lands in the cup 18.

The great economy in the manufacture 100 of this device is one of its outstanding features and in the manufacture thereof a single printing plate 3 may be provided whereby 105 at one impression, the game may be printed upon a flat strawboard base and simultaneously with the printing operation, the shallow ball indentations 4 may be made. This means that there is no special embossing 110 or printing required other than above noted, and it permits the use of stock pieces 115 of straw or other kind of cardboard for the

purpose and is very economical to manufacture, permitting this game device to be sold at a nominal price.

The indentations 4 for receiving the ball 5 are surrounded by printed symbols or designs in representation of the desired stations as the play may indicate, and in the present instance a square rectangular symbol is adopted to represent the greens and 10 a circle surrounding an indentation is adopted to represent the cup, and in the play of this particular game embodiment, the play is from green to cup and from cup to next succeeding green, and so on. These sequences of play stations may be arbitrarily arranged in any suitable or desirable manner.

The indentations themselves are extremely shallow and are such as might be made during 20 the printing operation in an ordinary printing press so that the indentations so made as station stops for the steel ball are particularly shallow and of such a nature as to provide a mere resting place for the ball, providing the skill of the player is such as to hold the game board in a proper level position and in such a manner as to give the ball a chance to come to full rest, otherwise the ball rolls freely out of the indentation and has to be brought back in this sequence of play from the station from which it escaped. This game requires a considerable amount of skill and body balance because of the fact that the operative field in which the ball is played or rolled in a flat plain surface and without any mechanical obstructions whatever, aside from the above noted shallowly indented play stations as noted.

40 No implements of any kind are utilized in the play of this game, the game box being covered by a glass plate and the ball is not accessible to the player, except through the rocking or tilting of the entire game box, and depending upon the skill of the player in such tilting and balancing the ball may be caused to gradually approach a station to drop into the shallow indentation in the sequence of play and thence moved out to the successive station, and so on.

The outstanding factor in a play of this game is the play against time, for granted that one player may be more skilled in balancing than another, then he will be more able to easily manipulate the ball through the tilting of the game box, and so control the ball to bring it at rest at the desired station, and an unskilled player will have considerable difficulty in controlling the ball through tilting the box, with the result that the ball will run at random without being under control, and which therefore, consumes more time in running the sequence of the play, so that a skilled player can play the sequence from beginning to end much

more rapidly than an unskilled one, and he therefore becomes the winner under the rules of this game.

What I claim is:

1. A game board comprising a ball, and a flat base provided with a plurality of depressions arranged in pairs, the depressions of each pair being closely adjacent to each other; said base being also provided with lines connecting the depressions in series; 70 said lines passing from each depression of a pair to the other depression of the same pair, and from one depression of each pair to a depression not of the same pair therewith.

2. A game board comprising a box having a flat bottom provided with a plurality of depressions arranged in pairs, the depressions of each pair being closely adjacent to each other; said bottom being also provided with lines connecting the depressions 80 in series; said lines including short lines passing from each depression of a pair to the other depression of the same pair, and long lines extending from one depression of each pair to a depression not of the same 90 pair therewith; and a ball in said box.

3. A game board comprising a box having walls and a flat bottom free of upward projections and provided with a plurality of depressions arranged in pairs; said bottom 95 being also provided with lines connecting the depressions in series; said lines passing from each depression of a pair to the other depression of the same pair, and from the depression of each pair to a depression not 100 of the same pair therewith; and a ball in said box.

4. A game board comprising a flat base provided with a plurality of intermediate depressions arranged in pairs, the depressions of each pair being closely adjacent to each other, one depression of each pair being round to represent a cup and the other being square to represent a tee; said base being also provided with an initial square depression marked Tee and a final round depression to represent the final cup, and lines connecting all of the intermediate depressions in series between said marked depression and the final depression, said lines passing from each round depression of a pair to each square depression of the same pair, and from each square depression to a round depression not of the same pair therewith; and a small movable member adapted to be 110 placed on said base.

5. A game board comprising a box having a flat bottom provided with a plurality of depressions arranged in pairs, the depressions of each pair being closely adjacent to each other, one depression of each pair being round to represent a cup and the other being square to represent a tee; said bottom being also provided with lines connecting 125 depressions, said lines passing from each 130

round depression of a pair to each square depression of the same pair, and from each square depression to a round depression not of the same pair therewith; and a ball in 5 said box.

6. A game board comprising a box having a flat bottom provided with an initial depression, a final depression and a plurality of intermediate depressions arranged in 10 pairs, the depressions of each pair being closely adjacent to each other; said bottom being also provided with lines connect-

ing all of the intermediate depressions in series between said initial depression and the final depression, said lines extending from 15 one depression of a pair to the other depression of the same pair, and from one depression of each pair to another depression not of the same pair therewith; and a ball in 20 said box.

Signed at New York, in the county of New York and State of New York, this 23rd day of November, A. D. 1923.

DAVID B. CONKLIN.
